UNITED STATES PATENT OFFICE.

JAMES ALEXANDER BRIMS, OF TARINGA, NEAR BRISBANE, QUEENSLAND, AUSTRALIA.

COMBINATION DRY AND STEAM HEATING APPARATUS.

Application filed July 24, 1922, Serial No. 577,257, and in Australia November 25, 1921.

This invention has for its object the provision of an improved apparatus for dry and steam heating, and although it is particularly designed for use in the dental laboratory for the manufacture of vulcanite dentures, for sterilizing, and other heating purposes, its adaptation for other, such as household, purposes, will be readily understood.

In carrying out my invention I provide a boiler, a heating chamber having a number of compartments, a water tank, means for controlling the supply of water from the tank, and passages and pipes for the passage of steam round and through the respective compartments. These and other details will be clearly set forth in the following description, reference being made to the accompanying drawings, in which

Fig. 1 is a vertical sectional view partly broken away on the line 1-1 of Fig. 2. Fig. 2 is a horizontal section on the line 2-2 of Fig. 3. Fig. 3 is a side elevation of the apparatus partly broken away. Fig. 4 is a fragmentary detail perspective of one of the doors of the apparatus.

The boiler 5, which is supported on legs 6, is rectangular in shape. The bottom 7 is shaped so as to form a float well 8.

The heating chamber 9, which is placed above the boiler 5, has double walls, floor, and roof, and is divided into a number of compartments 10 by horizontal and vertical double partitions 11.

Steam spaces 12 are thus formed around and between the compartments 10.

Trays 13 may be provided in the upper or either of the compartments 10. Steam tight doors 14 and 15 are fitted to the compartments 10. Figure 4. The door 15 may be provided with holes 16 and a damper plate 17, by which the passage of air through the compartment 10, out of holes 18 in the roof, through the space 19 at the top, to and through the outlet 20, may be regulated. The trays 13 do not reach to the back of the compartment.

Perforations 21 are provided in the roof of the boiler 5 so that communication is formed between the latter and the steam spaces 12.

The water tank 22 is placed above the heating chamber 9. It is provided with covers 23.

A steam pipe 24 establishes communication between the top of the steam spaces 12 and the water tank 22.

Steam pipes 25 fitted with cocks 26 form communication between the steam spaces 12 and the respective compartments 10.

Pipes 27 lead from the bottom of the respective compartments to the atmosphere.

A drain pipe 28 leads from the bottom of the lower compartments 10 to the bottom of the boiler 5.

The tube 29, which leads from the top of the boiler 5, has a diaphragm 30 near the bottom thereof, in which is fitted a valve seat 31. The valve 32 is carried by a tube 33 attached at the bottom to and opening into the float 34 and extending to and above the water level in the tank 22. The tube 29 may be made removable for inspection. A branch pipe 35, fitted with cock 36, leads from the bottom of the tank 22 to the tube 29.

A float 37 in the water tank 22 is carried by the rod 38 articulated to the lever 39 carried on the shaft 40 supported in bearings on the boiler 5 or back of the heating chamber 9. A lever 41, which is also carried by the shaft 40, is formed and arranged so that it can be caused to press on the rubber gas pipe 42 to the gas burner 43 to operate an electric switch or tap of an oil burner.

A tap 44 is provided on the boiler 5, and to it is fitted a flexible tube 45 having a nozzle 46 and shut-off lever 47.

A drain cock 48 is fitted on the water tank 22.

A ball cock 49 fitted to the water service may be provided in the tank 22 and, if desired, a similar ball cock 50, fitted to the water service, may be provided in the boiler 5.

In constructing heaters according to my invention I may vary the constructional details as found desirable, so long as the essential features are retained.

The operation of my invention is as follows:—

Water, placed in the tank 22, finds its way past the valve 32 into the boiler 5 until it reaches the desired level, when, by the action of the float 34, the valve 32 is closed. This float 34 and valve 32 regulate the supply of water from the tank 22 to the boiler 5. The water in the tank 22 quickly becomes

hot, not only owing to its position, but because of the fact that the used steam from the steam spaces 12 ascending through the pipe 24 enters and condenses therein.

5 As steam is generated in the boiler 5 it passes up between the walls, floors, and partitions of the chamber 9, through the steam spaces 12 and pipe 24 to the tank 22 where it condenses. This passage of steam around 10 the various compartments, dry heats the interior thereof.

When it is desired to steam heat an article in any compartment 10 the desired cock 26 is opened and steam allowed to pass from 15 the steam spaces 12 through the pipes 25 into the compartment and then through the pipes 27 to atmosphere. Any condensed water in the lower compartments 10 finds its way to the bottom of the boiler 5 by the 20 pipe 28.

The water level in the boiler 5 is regulated by the action of the float 34 and valve 32. The supply of gas or oil to the burners or 25 the electric current to electric heaters is regulated by the float 37 in the tank 22 and acting on the shut-off lever 41, which in the case of gas or oil supply, presses on and closes the flexible pipe; in the case of an electric heater it acts on a switch.

30 Hot water for scalding purposes is supplied through the tube 45, the supply being controlled by the spring lever 47, which nor-

mally closes the tube 45, but which latter may be opened by pressure on the lever 47, releasing the tube 45. Hot water can also 35 be taken from the tank 22 by the tap 48.

Having now particularly described and ascertained the nature of my said invention and in what manner the same is to be performed I declare that what I claim is:—

1. In an apparatus of the character described, a boiler, a heating chamber having a plurality of compartments arranged above 45 the boiler, the walls of said compartments being hollow to provide steam passages communicating with said boiler, valve controlled means for conducting steam from the steam passages to the interior of the respective compartments, a water tank overlying the uppermost heating chamber, valve controlled 50 means for conducting water from the tank to the boiler, and means permitting the escape of steam from the respective compartments to the atmosphere.

2. An apparatus as claimed in claim 1 including float operated means controlling the passage of water from the tank to the boiler, means for controlling admission of water to the tank, a heater associated with the boiler, and float controlled means for controlling 55 the heater.

In testimony whereof I affix my signature.

JAMES ALEXANDER BRIMS.
